UNITED STATES PATENT OFFICE

2,007,236

TOBACCO STRIPPING MACHINE

Louis H. Zeun, Baltimore, Md., assignor of one-third to Albert W. Adt and one-third to John B. Adt, both of Baltimore, Md.

Application August 18, 1931, Serial No. 557,833
Renewed October 9, 1934

11 Claims. (Cl. 131—57)

The invention relates to tobacco stripping machines and has as an object the provision of a machine that will separate the blades and stems of tobacco leaves from each other, doing little damage to the leaves.

It is a further object of the invention to provide a tobacco stripping machine that will strip the butt portions of the leaves from the stems and separately strip the remaining portions delivering the two portions thus stripped, separately.

It is a further object of the invention to provide a machine that will strip the leaf material from the stems without breaking the stems and in so doing will conserve substantially all useable portions of the leaf.

It is a further object of the invention to improve upon the structure described and claimed in Patent No. 1,879,651 granted to me under date of September 27, 1932, in the following details: the leaf supply belt drive; the leaf separating means; the leaf feeding means; the stem butt cutting means and the stripper hold down means.

Further objects of the invention will appear from the following description when read in connection with the accompanying drawings showing an illustrative embodiment of the invention and wherein:—

Fig. 1 is a perspective view showing the front of the machine and the feed end thereof;

Fig. 2 is a perspective view of the front of the machine and the delivery end thereof;

Fig. 3 is a plan view of the left-hand or feed end of the machine with a portion of the mechanism thereof above the table omitted from the right hand end of the view;

Fig. 4 is a plan view, being substantially a continuation to the right of Fig. 3;

Fig. 5 is a detail end elevation of the left-hand end of the machine seen from the front upon an enlarged scale;

Fig. 6 is a detail view of the drive mechanism viewed from the right of Fig. 5;

Fig. 7 is a detail side view of a portion of the drive shown in Fig. 5 upon an enlarged scale;

Fig. 8 is a detail vertical section on line 8—8 of Fig. 3;

Fig. 9 is a side elevation upon an enlarged scale of a leaf separating means;

Fig. 10 is a section on line 10—10 of Fig. 9;

Fig. 11 is a side elevation of a second leaf separating member;

Fig. 12 is a perspective view of the strippers showing the leaf clamping means swung upwardly;

Fig. 13 is a vertical section on line 13—13 of Fig. 14 upon an enlarged scale;

Figs. 14 and 15 are detail sections on the corresponding lines of Fig. 13 upon an enlarged scale;

Fig. 16 is a side view of the structure shown in Fig. 14;

Fig. 17 is a detail side elevation of a portion of the stripping mechanism showing but two stripper blades;

Fig. 18 is a detail side elevation of the leaf clamping mechanism a portion of which is shown in upwardly swung position in Fig. 12;

Fig. 19 is a plan view of the table at the right end of the machine with the mechanism thereabove cut away;

Fig. 20 is a detail plan view of the stem butt serving means;

Fig. 21 is a section on line 21—21 of Fig. 20;

Fig. 22 is a side elevation of the cutting means of Fig. 20 showing the discharge chute in section;

Fig. 23 is a section on line 23—23 of Fig. 24, upon a slightly reduced scale;

Fig. 24 is a bottom plan view of a stripper drive mechanism;

Fig. 25 is a detail side elevation of the butt stripping mechanism;

Fig. 26 is a view similar to Fig. 25 with parts omitted for clearness;

Fig. 27 is a section on line 27—27 of Fig. 25;

Fig. 28 is a side elevation taken from the rear end of the machine at the delivery end thereof;

Fig. 29 is a detail vertical section on line 29—29 of Fig. 30;

Fig. 30 is a vertical transverse section on line 30—30 of Fig. 29;

Fig. 31 is a detail front elevation partly in section on line 31—31 of Fig. 33;

Fig. 32 is a detail vertical section on line 32—32 of Fig. 31;

Fig. 33 is a detail vertical section on line 33—33 of Fig. 28;

Fig. 34 is a detail side elevation upon an enlarged scale of a portion of the stripping mechanism showing the means for varying the elevation of the stripper blades in their movement;

Fig. 35 is a section on broken line 35—35 of Fig. 34;

Fig. 36 is a vertical section on an enlarged scale taken on the corresponding line of Fig. 2;

Fig. 37 is a horizontal section on the corresponding line of Fig. 36;

Fig. 38 is a detail vertical section of the stem removing roller pressure regulating means;

Fig. 39 is a horizontal section upon line 39—39 of Fig. 38;

Figs. 40 and 41 are detail horizontal sections upon much enlarged scales through the end of 5 the stripper blades illustrative of their action in removing leaf material from the stems;

Fig. 42 is a detail side elevation of a stem elevating means showing a stripper blade in edge view;

10 Fig. 43 is a vertical section upon an enlarged scale on line 43—43 of Fig. 44; and

Fig. 44 is a detail side elevation of a stem scoring means showing a portion of the leaf gripper housing in section.

15 As shown the mechanism of the device is supported upon a table 50 supported upon legs 51, upon which table for conveyance of tobacco leaves to be stripped, there are shown a plurality of belts 52, 53, 54, 55, 56, 57, 58, the belt 55 being 20 shown in Figs. 3, 12, and 19.

For drive of the mechanism of the apparatus, there is shown a belt pulley 59 mounted beside a loose pulley 60 upon a shaft 61 bearing a sprocket 62, Fig. 4, about which a chain 63 is carried driving a sprocket 64 fixed upon a shaft 65, which shaft 65 drives the entire mechanism of the device with the exception of stripping rollers to be described.

To drive the belts 52, 53, and 54, there is shown 30 a gear 66 upon the end of shaft 65 in mesh with a gear 67 keyed upon a shaft 68 mounted in bearings 69, 70 having a crank 71 upon its ends in the form of a T-shaped member coacting with a member 72 adjustable thereon by releasing set 35 screw 72' and provided with a pin 73 upon which is mounted a link 74 pivoted to a vertically reciprocable connecting rod 75 connected by means of a link 76 with one arm of a bell crank 77, the other arm of said bell crank being connected to 40 a link 78 attached to a swingable arm 79 pivoted at 80.

Also connected to the pivot 81 by which the arm 78 is attached to the arm 79, are connected two pairs of links 82, 83 connected at their opposite ends to pins 84, 85 supported in arms 86, 87, which arms are loose at their inner ends upon shaft 88. The pins 84, 85 also carry pawls 89, 90 spring pressed to engage the teeth of a ratchet wheel 91 fixed upon shaft 88 upon which are 50 mounted a plurality of pulleys 92, 93, 94 about which the belts 52—54 inclusive pass to be driven thereby.

The said belts 52—54 inclusive also pass about 55 pulleys 95, 96, 97 loose upon a shaft 98, the ends of said belts dipping under the surface of the table at the point of over-lapping thereof with the belts 56, 57, and 58, each of the belts upon the table preferably traveling in slots in the surface of the table.

60 The drive of the belts 55—58 inclusive, pulleys 99, 100, 101, and 102 are fixed upon the shaft 98, which shaft is driven by sprocket 103 by means of chain 104 passing about sprocket 105 fixed upon shaft 106 bearing gear 107 in mesh 65 with the gear 108 fixed upon shaft 109 bearing sprocket 110 driven by chain 111 passing about sprocket 112 fixed upon stub shaft 113 driven by a worm drive 114 from shaft 65.

The belts 56, 57, 58 are passed about a drum 70 115 mounted upon a shaft 116 carried by bearings 117, 118 at the delivery end of the table.

The bearings 117, 118 of shaft 116 are shown as 75 slidable to adjust the tension of the belts 56—58 inclusive. The belt 55 which is shorter than the belts 56—58 inclusive terminates at the

point shown in Fig. 19, passing around an idle pulley mounted upon a shaft 119, the end of which shaft is carried by bracket 120.

To align the ends of the stems of the tobacco leaves, there is shown a guide fence 121 rising from the table at its feed or right-hand end shown at the left of Fig. 1. To separate the stems of the leaves as they are fed to the mechanism, a pair of pulleys 122, 123 are shown in detail in Figs. 9—11 inclusive, which pulleys have 10 projections 124, 125 carried by plates 126, 127 attached to one face thereof as by screws 128, 129, the said pulleys being mounted upon shafts 130, 131 and being grooved for reception of belt 132, which belt also passes about a pulley 133 mounted upon shaft 134. The pulleys 122, 123 are idle upon their shafts and pulley 122 is shown as mounted in adjustable bearings whereby the tension of the belt may be controlled.

To drive the belt 132 and the pulleys 122, 123, the shaft 134 is shown as provided with sprocket 135, Figs. 2 and 3, about which chain 136 is passed, the chain passing about idlers 137 and 138 and about sprocket 139 fast upon shaft 88 for drive.

The peripheral speed of the belt 132 and of pulleys 122, 123 is preferably slightly greater than that of belts 52—54 inclusive whereby stems of tobacco leaves acted upon by projections 124, 125 and the belt 132 will be advanced through 30 a distance faster than they are fed by the cable belts, thus causing the stems to be separated. As a means for additionally separating the stems there is shown a belt 140 passing about pulleys 141, 142, pulley 141 being mounted in bearings 35 carried by the end of the arms 143, 144 pivoted at their opposite ends upon shaft 109.

To hold the pulley 141 slightly above the path of the stems, the arms 143 are shown as projecting beyond the shaft 109 at 145 impinging 40 against an adjustable stop screw 146 mounted in a lug upon the frame of the device. The pulley 142 is shown as mounted in adjustable bearings in plates 147, 148 freely movable at their forward ends upon shaft 149 upon which the 45 pulley 141 is keyed, whereby the rear end of the belt 140 may drop by gravity into contact with the tobacco stems.

To drive the shaft 149, pulley 141, and belt 50 140, the shaft 149 is provided with a sprocket 150, Fig. 3, driven by a chain 151 passing about a sprocket 152 keyed upon shaft 109.

To strip leaf material from the stems of tobacco leaves, applicant utilizes two sets of strippers each embodying similar but not identical 55 stripper plates. One of said strippers is used to strip material of the leaves adjacent the butts of the stems and deliver the same separated from the remainder of the leaf material which is later stripped from the stems and delivered at the left 60 hand end of the machine, the stems being delivered at the front side of the machine separately from the butt leaf material. Means are also provided to cut off the butt ends of the stems which often carry a protuberance or enlargement which 65 might interfere with the action of the final stripping.

For the purpose of stripping the butts of the leaves, the strippers shown in Figs. 26, 27, and 28 are provided, and for stripping the remainder 70 of the leaf the strippers shown in Figs. 28, 29, 30, and 34, among other figures, are provided. In the stripping of the butt portion of the leaf, the leaves are carried continuously along the machine in a direction parallel with its length and 75

the stripping mechanism for butting moves in a path at an angle to the table of the machine, the component of movement thereof parallel with the table of the machine being at the same speed as the movement of the leaves along the table so as to place no transverse strain upon the stems.

To support the stripping mechanisms, and control their drive, a housing 153 is provided above the table supported upon standards 154, shown in 10 section in Fig. 3, and 155, shown in Fig. 2, and in section in Fig. 19.

The butt stripping mechanism comprises a plurality of stripper plates 156 each secured by means of a bolt 157 to a sliding plate 158 having an angularly projecting portion 159 at its upper extremity. The plates 158 are each provided with a slot 160 and as shown in Fig. 37 in connection with the final stripping plates, the portions 161, 162 of the plates 158 slide in rabbets in a block 163, being 20 retained therein by means of a block 164, a cap screw 165 being provided to retain block 164 in position. The block 163 is as shown in Fig. 27 also grooved to receive the separated teeth 166, 167 of sprocket wheels 168, 169 provided to drive 25 the strippers.

The blocks 163 are connected with each other by links 170 as plainly indicated in Fig. 37.

The sprocket 169 is shown as keyed upon a shaft 171 journaled in the housing 153 and driven by 30 means of a worm wheel 172, Fig. 25, through the medium of a worm gear 173 mounted upon a shaft 174, which shaft 174 is driven by gearing housed in casing 175, Fig. 2, which gearing is similar to that to be described in the final stripping mechanism.

The sprocket 168 is shown as mounted upon a shaft 176 fixed in a movable block 177 clamped to the frame by means of a cap screw 178, which movable block may be adjusted to tighten the chain by loosening the screw 178 and by manipulation of the adjusting screw 179, see Fig. 23.

To control the elevation of the stripping plates 156 to raise the same from operative position and to lower them to this position, the portions 159 of the plates 158 are shown traveling upon a track 180 at the lower level and 181 on the upper level. To lift the plates from the lower to the higher level, there is shown an incline 182, Fig. 26, and the upper level 181 terminates at 183, Fig. 26, to allow the stripper plates to drop. To force the said plates down into straddling relation to the stems of the leaves, there are shown a plurality of spring actuated levers 184 each pivoted to a bar 185 spaced from a plate 186 having an upper flange 187 overhanging the levers.

The levers 184 are shown as pivoted at 188 between the bar 185 and the plate 186 and as projecting above the pivot to which projection a spring 189 is attached in connection with each lever, which springs are anchored at 190 upon the flange 187. The levers 184 are alternately staggered upon their pivots 188, as shown in Fig. 27, so that they may move past each other as indicated at the left of Fig. 25.

As the plates 158 approach the end 183 of the track, the projection 159 of the plates contacts with an edge of the first lever thereby placing pressure upon the plate in a downward direction to force it into contact with the incline 191 of the lower level of the track.

The stems of the leaves as they reach the plane of the butting stripper extend over spaced plates 192, 193, Fig. 27, between which plates the stripper plates 156 project. The stripper plates are provided with recesses, as shown, so

as to enable them to coact with stems of varying thicknesses and edges of the prongs are so formed as to in effect form recesses between the stripper plates also for the same purpose. The butting stripper plates being pressed astride the stems and being moved at an angle thereto so as to be given in effect a movement lengthwise of the stems toward the butt thereof act to strip off the leaf material from the butt of the stem and deliver the same to the chute 194, Fig. 2.

To hold the stems against the pull of the butting operation, the mechanism illustrated in Figs. 13 to 18 is provided comprising upper clamping mechanism 195 and lower clamping or supporting mechanism 196.

As shown the lower mechanism comprises a plurality of shoes 197 desirably made of wood or the like, each shoe secured by members 198 to the links 199 of a sprocket chain passing about sprockets 200 and 201 mounted upon shafts 106 20 and 202 respectively.

The shoes 197 travel in a cut-out portion in the table so as to directly support the belt 54 below its upper run. To give support for the upper run of the chain to prevent flexure thereof, there is shown a strip 203 upon which rollers 204 carried by the sprocket chain may travel as indicated in Fig. 14.

Coacting with the mechanism 196, the mechanism 195 comprises a plurality of shoes 205 each 30 shoe carrying in a recess in its lower portion a pad 206 preferably formed of resilient material as rubber, the shoes 205 being mounted upon the links 207 of a sprocket chain similar to the links 199 of the lower chain, which links 207 carry rollers 208 coacting with a strip 209 in their lower run, the sprocket chain passing about a driven sprocket 210 mounted upon shaft 109 and about an idle sprocket 211 mounted on shaft 212. The shaft 212 is journaled in a frame 213 attached 40 to the housing 153 as by means of cap screws 214. The cap screws 214 may be removed whereupon the frame 213 may be swung about shaft 109 to the position shown in Fig. 12 to give access to the mechanism hidden thereby.

The strip 209 is shown as stressed downwardly by compression springs 215 mounted in recesses in the frame 213 and is of such form and the elevation of the sprockets 210 and 211 is such, that the plane of the pads 206 gradually approach 50 the belt to a portion of the greatest clamping pressure upon the leaves being stripped and gradually recede from the plane of the belt, as clearly shown in Fig. 13.

The position of greatest pressure upon the 55 leaves is opposite the portion of travel of the leaves wherein they are being acted upon by the butting strippers.

The mechanisms 195 and 196 are driven at the speed of the belt. By the means shown at 216, 60 Fig. 18, the bearing of shaft 212 may be moved to adjust the tension of the mechanism 195.

To support the upper run of the shoes 205, and chain 207, a rib 217 is shown in a hollow between the two side walls 218, 219 of the casting 65 213, the rollers 208 traveling upon the rib 217.

The stripper plates 156 travel in the path indicated by dot and dash lines 222, Fig. 20, the remaining set of stripper plates, to be described, traveling in path 223, shown in the same figure.

To cut off the butt ends of the stems of the leaves the scissors arrangement shown in Figs. 20, 21, 22 is provided comprising a knife blade 224 bolted to a lever 225 by means of bolts 226. Thumb screws 227 are provided which push the 75

- knife blade toward its ledger plate 228, Fig. 21, to adjust the cutting action. For actuation of the lever 225, the same is shown as mounted upon a shaft 229 mounted in a sleeve 230 carried by bracket arms 231, the end of shaft 229 having a crank arm 232 terminating in a ball 233 having a bearing in the end of a link 234 vertically oscillated by an eccentric 235 mounted upon shaft 65, see Fig. 2.
- 10 The ledger plate 228 is supported by means of a plate 236 carried by arms 237.
- 15 A cover plate 238 is provided for the belt 55 adjacent the butt cutting scissors, and the severed butts fall into a chute 239 for delivery from the machine.
- 20 To strip the portion of the leaves adjacent the tip of the leaf, a plurality of stripper plates 240 are shown, which are similar to the plates 156 but travel parallel with the travel of the leaves, and the stripping action in this instance is accomplished by withdrawing the stems from the material of the leaves against the relatively stationary stripper plates 240. The stripper plates 240 are mounted upon blocks carried by sprocket 25 chains traveling about sprockets 241, 242. The sprocket 241 is mounted to revolve freely upon the shaft 243 fixed in a bearing 244 mounted for adjustment to vary the tension of the chain, which adjustment may be accomplished by 30 means of screw 245 and nut 246 and which bearing may be clamped in adjusted position by means of clamp screw 247.
- 35 The sprocket 242 is fixed upon shaft 248 mounted in a sleeve 249 and driven by worm wheel 250 and worm gear 251 mounted upon shaft 252, which shaft is driven by gears 253, 254, the latter being keyed upon shaft 65.
- 40 The stripper plates 240 and their carrying blocks and sprocket chains are similar to those already described in connection with stripper plates 156.
- 45 To control the elevation of the plates 240, the angular projections 255 thereof travel upon a track 256 which holds the stripper plates elevated in the non-active portion of travel. In Fig. 35 the plates are shown depressed at the left side of the figure and elevated upon the right side of the figure. To lift the plates from the depressed to elevated position, the inclined plane 50 257, Figs. 17 and 29, is provided and to allow the plates to drop to their lower position the configuration shown at 258, Fig. 17, is provided.
- 55 To elevate the stems of the leaves whereby the stripper plates 240 may become engaged astride the stems, the knurled edged wheels 259, 260, each provided with a slot in its periphery, are shown in plan in Fig. 19, the stripper plates traveling through the slots in the wheels and the periphery of the wheels rising above the plane of 60 the ledger plates 192, 193.
- 65 To drive the wheels 259, 260, the shafts 261, 262 upon which they are mounted are provided with sprockets 263, 264 about which passes a chain 265, which chain also passes about a sprocket 266 on shaft 267 extending under the table and carrying a sprocket 268 driven by chain 269, which chain is driven by sprocket 270 upon shaft 106.
- 70 As the stripper plates 240 come above the wheel 259 they drop to the level 271, Fig. 17, and again to the lower level 272 over the wheel 260, thereby becoming firmly fixed astride the stems. It is desirable to adjustably vary the elevation of the plates 240 as the stems are being withdrawn therefrom to suit variation in the sizes of the stems. For this purpose a portion of the track upon the level 272 is formed in sections as diagrammatically indicated at 273, Fig. 17, the sections of the track being pivoted together, and the pivots being connected to links 274, 275, 276. The respective lengths are pivoted to the ends of the crank arms 277, 278, 279, which arms may be revolved for adjustment by means of arms 280, 281, 282, Figs. 34 and 35, the last named arms being fixed upon shafts 283, 284, 285, upon which the arms 277-279 are secured and may be clamped in adjusted position by means of knurled heads 286, 287, 288 respectively, carried by bolts 289, bearing nuts 290 traveling in grooves 291 in the back of the casting and the bolts 289 traveling in arcute slots 292. The last element of the sectional track is shown as pointed at its end 293 so as to smoothly deliver angular projections 255 to the successive portion of the track upon the level 272.
- 20 To prevent the stems from rising as they are withdrawn from the leaf material, there is shown in Fig. 34 a plate 294 pivoted upon a shaft 295 and provided with a counterweight 296 adjustable upon the stem 297 projecting from the hub 25 of the pivot, which hub also is provided with a lug 298 adapted to contact with a set screw 299 to limit the upward movement of the plate 294, the plate 294 lying closely adjacent the sides of the stripper plates 240.
- 30 The stripper plates 240 are shown as resiliently depressed by means of levers 184' similar to the levers 184 already described with the butting stripper plates. These levers are grouped so as to apply pressure upon the stripper plates over the wheels 259, 260 respectively and over the sectional portions 273 of the track, which arrangement is clearly shown in Fig. 29. By this grouping, pressure is only applied upon the stripper plates where necessary and the strain upon the stems and the power required to drive the machine is thereby reduced.
- 35 To withdraw the stems from the leaves while the leaf material is held by the stripper plates 240, stripping rollers 300, 301 are shown in Figs. 2, 19, 28, 35, and 36, the roller 300 being mounted in bearing 302 and its shaft carrying a gear 303 in mesh with an idle gear 304 in mesh with a gear 305 on shaft 61, the gear 303 being in mesh with the gear 306 upon the shaft of roller 301.
- 40 The shaft of roller 301 is mounted in a bearing 307 having a stub shaft 308 projecting therefrom, which stub shaft is journaled in an eccentric bushing 309 carried in bracket 310. The roller 301 is thereby pivoted for slight movement about the shaft 308, the loose fit between the gears 303-306 permitting of the slight pivotal action. The free end of shaft 301 is journaled in a bar 311 carried by an arm 312 projecting from the bearing 307 and a set screw 313 is provided as a stop for the vertical swinging motion of the arm 312 and roller 301, which set screw may be adjusted to limit the upward movement of the arm.
- 45 The eccentric bushing 309 has a serrated edge 314 within a selected one of which serrations a set screw 315 is placed to hold the bushing in its position of rotation. By removing the set screw 315, the eccentric bushing may be rotated to adjust the space between the fixed ends of the rollers 300, 301. The ends of the rollers between which the projecting butts of the stems enter in their travel with the conveyor belts upon the table are shown as carrying coarse threads at 50 316, 317, Fig. 31, and a shoe 318 carried by the 55 316, 317, Fig. 31, and a shoe 318 carried by the 60 316, 317, Fig. 31, and a shoe 318 carried by the 65 316, 317, Fig. 31, and a shoe 318 carried by the 70 316, 317, Fig. 31, and a shoe 318 carried by the 75 316, 317, Fig. 31, and a shoe 318 carried by the

bearing 311 is shown in the same figure for guiding the butt ends of the stems between the rollers. The rollers 300, 301 are driven at a considerable speed so that as the stems are engaged by the 5 rollers they are very rapidly withdrawn, causing the leaf material to be stripped from the stems by action of the stripper plates 240.

To place pressure upon the rollers to cause them to grip the stems, there is shown a rod 319 10 bearing against the end of the arm 312 projecting upwardly through the housing 153 carrying a collar 320 against which acts a spring 321, Fig. 38, said spring abutting against an adjustable sleeve 322, the adjustment of which may be varied 15 by means of a squared head 323.

To release the pressure upon spring 321, there 20 is shown in Fig. 38 a cam 324 pivoted at 325 upon the top of housing 153 and having a cam finger projecting under the collar 320, the cam 25 having an incline 326 by which the collar may be raised to remove the pressure of spring 321 from the arm 312.

The lifting action of wheels 259, 260 is clearly 25 shown in Fig. 42 and the bevel of the edges of the stripper plates 156 is illustrated in Fig. 40 wherein in the stem of the leaf is relatively stationary and the stripper plate has the relative motion in the direction of the arrow in said figure. The bevel of the edges of the prongs of the stripper plates 30 300 is illustrated in Fig. 41 wherein the stems of the leaves have a motion relative to the stripper plates illustrated by the arrow in said figure.

To notch or score the stems so that the upper 35 portions of the same may break to permit their withdrawal from the leaves, a scoring knife illustrated in detail in Fig. 43 is shown. This knife mechanism is supported by the angle arm 327, as shown in Fig. 1, carried by the frame member 213.

40 Journaled in arms 328 projecting from the arm 327 is a shaft 329, which shaft is driven by a sprocket 330, chain 331, and sprocket 332 on shaft 109.

Slidably mounted with a feather upon shaft 45 329 is a sprocket 333 driving chain 334 which in turn drives sprocket 335 upon a shaft mounted in arm 336, which shaft bears the disk cutter 337. The arm 336 may be adjusted longitudinally of the arm 327 by the means shown in Fig. 44 and may 50 be clamped in adjusted position by means of belt 338. By means of set screws 339, 340, the elevation of cutter 337 above the table may be adjusted so as to determine the depth of the scoring of the stems.

55 In operation of the machine, the leaves are placed upon the conveyor belts 52, 53, 54, by the attendant and roughly separated by hand, the butts being brought into contact with the fence 121 to align the same, then spaced apart by the wheels 122, 123 which, as has been stated, revolve at a speed in excess of the underlying conveyor belts. The leaves are next gripped by the belt 140, flattened down and delivered to the gripper blocks 195 to be clamped between these blocks and the belt as supported by the opposed blocks underneath the same. Since the gripper blocks act against a considerable portion of the area of the leaves, the leaves are held against the pull of the initial butt-stripping operation without damage to the leaf material. So held the leaves are advanced and the butts are trimmed off by means of the scissor-cutting mechanism of Fig. 20.

The butt stripping plates illustrated in Fig. 25 are at this point depressed into straddling contact with the stems, the point of depression be-

ing that at which the plane of the stripper plate is substantially perpendicular to the length of the stem and as the stripper plates proceed to follow the path diagonal to the stem, the plates receive a movement of rotation with respect to the length of the stems thereby increasing the pressure of the edges of the stripping recesses against the stem itself.

In the subsequent portion of the movement of the leaves, the butt portions of the stems are cleared, the thus removed leaf material being delivered to the chute 194. The stems are then carried along and subsequently lifted by wheels 259 and 260 into engagement with the descending stripper plates of the second set shown in Fig. 28. 10 So engaged the stems are carried to the rapidly revolving rollers 300, 301 being separately fed between the rollers by the helical ends 316, 317 thereof, which rollers grip the bared portion of the stems and jerk the stems away from the leaf material, the stems having been already gashed or weakened by the knife 337 by means of the mechanism shown in Figs. 43, 44.

In the action of the second set of stripper plates the depressing levers 184 are grouped 15 above the wheel 259 and above the wheel 260 and also over the range of the actual stem-withdrawing portion of travel of the leaves so that travel of the stripper plates is not impeded by pressure thereon where it is not needed.

As the run of the leaves varies as to diameter 20 of the stems, the track illustrated in Figs. 17 and 29 is adjusted to fit the conditions so as to not allow the stripper plates to press upon large stems more than is necessary and may still be caused to firmly engage small stems.

In an emergency the pressure upon the upper 25 stripping roller 301 may be released by actuation of the handle 324 and the running pressure upon this roller can be readily modified by the mechanism shown in Fig. 28.

The speed of the belts 52, 53, 54, relative to the speed of the belts 55-58 may be readily adjusted by loosening set screw 72 and adjusting the block 72 to govern the throw of the pawls.

Minor changes may be made in the physical embodiment of the invention within the scope of the appended claims without departing from the spirit thereof.

I claim:

1. In a machine of the character described, in combination, stripping mechanism, and means adapted to cause relative stripping movement between said mechanism and the leaves to be stripped, said stripping mechanism including a unit gang of independent leaf strippers, strippers of which are independently mounted for relief movement transversely of the leaf-stems in the stripping operation, and have stem-receiving, 55 stripping apertures, flaring in a direction opposite to that of said relief movement, a device acting yieldingly and successively upon the individual strippers to restrain said relief movement of said independent strippers, and a device adapted to restrain the extent of transverse movement of the stems under pressure of said strippers.

2. In a machine of the character described, in combination, mechanism to strip leaf material from stems, conveyor belts to carry the leaves 70 through the range of the stripping operation, conveyor belts to deliver leaves to said first named belts, pawl and ratchet drive means for said last named belts and means to vary the throw of the driving ratchets whereby to vary the speed 75

of the last named belts relative to the speed of carried by said lever, means to adjust said scissor the first named belts.

3. In a machine of the character described, in combination, means to strip leaf material from

5 stems, a conveyor belt to deliver leaves to said means and means to separate successive delivered leaves comprising a pulley revolving above the delivery point of and faster than said conveyor belt, said pulley carrying stem engaging projec-

10tions.

4. In a machine of the character described, in combination, means to strip leaf material from stems, a conveyor belt to move the leaves through the stripping range of the machine, a slower run-

15ning second conveyor belt to deliver leaves to said first named belt conveyor, means to separate suc-cessive delivered leaves comprising a pair of pulleys mounted to revolve above said belt means and spaced longitudinally thereof, said pulleys carrying stem engaging projections and a driven and conveyor belt passing about said pulleys and traveling faster than either of said belt means.

5. In a machine of the character described, in combination, stripping mechanism, a conveyor belt to move leaves during action of said mech-anism, means to clamp leaves against said belt during a portion of the travel thereof, means to separate leaves delivered to said belt, and means coacting with said conveyor belt to deliver leaves from said separating means to said clamping means comprising a pair of spaced frame mem-bers, shafts journaled in said members, pulleys mounted on said shafts, a belt traveling about said pulleys, a pair of arms pivoted on a fixed portion 35of the machine and pivoted upon said frame mem-bers adjacent the front end thereof, adjustable means to limit the approach of said front end of the frame to the conveyor belt, the rear ends of said frame members under action of gravity about 40said last named pivots causing said belt to contact the leaves, and means to drive one of said pulleys.

6. In a machine of the character described, in combination, means to strip material from stems 45adjacent the butts thereof and means to sever the ends of said butts comprising a fixed ledger blade, a scissor blade pivoted adjacent and co-acting with said ledger blade and means to oscil-late said scissor blade.

50 7. In a machine of the character described, in combination, butt stripping mechanism, means to sever the ends of butts comprising a ledger blade fixed in advance of said mechanism and in the path of movement of stems to said mechanism, a lever pivoted adjacent said blade, a scissor blade

carried by said lever, means to adjust said scissor blade toward and away from the plane of said ledger blade and means to oscillate said lever about its pivot.

8. In a machine of the character described, in combination, a plurality of blocks, means to move said blocks in recurrent paths, stripper blades vertically slidable on said blocks, a track having portions in different horizontal planes, a track

10follower carried by each blade, means to yieldingly depress said followers toward the lower plane of said track comprising plates depending from fixed pivots, sloping in the direction of movement of the blocks and impinging against a portion of each blade as they move there-beneath.

15 9. In a machine of the character described, in combination, a plurality of blocks, means to move said blocks in recurrent paths, stripper blades vertically slidable on said blocks, a track above and 20adjacent the path of movement of said blocks and having portions in different horizontal planes, a track follower carried by each blade overlying said track, means to yieldingly depress said blades comprising levers mounted on fixed pivots above the depressed portion of said track, depending 25ends of said levers sloping in the direction of movement of said blocks and impinging upon said track followers as they move there-beneath and spring means to depress said depending portions.

10. In a machine of the character described, in combination, leaf stripping mechanism comprising a plurality of vertically slidable stripper blades, mechanism to move said blades in recurrent paths, a track having portions in different horizontal planes, track followers carried by said 35blades traveling on said track, a plurality of levers pivoted above a lower plane of said track closely adjacent each other in staggered vertical planes to lap past each other when moved about said pivots and resilient means to cause said levers to 40depress said track followers toward said track.

11. In a machine of the character described, in combination, leaf stripping mechanism comprising a plurality of stem engaging stripper blades, mounted for vertical sliding movement, 45means to move said blades in recurrent paths, means to lift stems of leaves to cause engagement with said blades in portions of one of said paths, means to cause stripping of the leaves in another portion of the one of said paths, a plurality of 50yielding blade depressing means common to all of said blades, said depressing means grouped above the named portions of said one of said paths.

LOUIS H. ZEUN.
